FIG-1

FIG-4

FIG-3

A cross-sectional view of a cylindrical container, likely a drum or tank. The container is shown in perspective, revealing its circular base. A vertical tube or pipe extends from the top center of the container. At the bottom, there is a valve assembly consisting of a circular base plate with a central opening and a handle or lever extending from the side. The container is marked with various numbers and letters: '8' is on the left side, '23' is at the top center, '22' is on the right side, '21' is at the bottom center, and '20' is on the far right side.

AIR FILTER MEANS

Albert E. Schaaf, Cleveland, and George M. Walton, Parma, Ohio, assignors to Air-Maze Corporation, Cleveland, Ohio, a corporation of Delaware

Application March 11, 1935, Serial No. 10,374

20 Claims. (Cl. 183—15)

This invention relates to air cleaner apparatus of the type including a filter element arranged to be maintained in wet condition by an associated liquid, a quantity of the liquid being also so arranged with reference to the air stream that entrained solid particles will be deposited in the liquid by their inertia and thus removed from the air stream. An example of such apparatus is disclosed in Patent No. 1,876,368 issued February 5, 1932 to G. M. Walton, and the objects of the present invention are generally to improve upon the air cleaner therein disclosed.

15 A particular object of the invention is briefly to provide that such a cleaner be capable of adjustment to function within a range of capacities, with the highest efficiency for any given conditions. It will be appreciated that the range of volumetric demand involves substantially different velocities through the cleaner. But removal 20 of solids from the air stream by inertia, has somewhat critical requirements as to velocity and direction of the air stream adjacent the liquid surface. This invention, therefore, embraces means for varying the operating characteristics 25 of the apparatus by adjusting the velocity of flow adjacent the surface of the liquid, relative to the velocity elsewhere in the path of the stream through the apparatus, whereby said velocity may be established as desired, for any given demand upon the apparatus.

For much the same general reasons a further object of the invention is to provide novel means tending to maintain the liquid quiescent, and its surface, therefore, stable against undue splashing action during motion of the apparatus, as when mounted on a vehicle.

Another object of the invention is to provide novel means for preventing access to the outlet of the apparatus, of any liquid carried which might otherwise find its way from the filter element in the direction of flow.

And still other objects are to provide improved means for attaining and maintaining the relation of certain parts of the assembly, and particularly access to parts for cleaning, all as will appear.

appeal.
The exact nature of this invention together with further objects and advantages thereof will be apparent from the following description taken 50 in connection with the accompanying drawings, in which Fig. 1 is an elevation partly in section and with parts broken away, illustrating a typical embodiment of the invention; Fig. 2 is a detail in perspective, showing parts appearing in Fig. 1; 55 Fig. 3 is a sectional detail as in the plane of line

3-3, Fig. 1; Fig. 4 is a sectional detail as in the plane of line 4-4, Figs. 1 and 3; Figs. 5 and 6 are sectional details as in the planes of lines 5-5 and 6-6 respectively, Fig. 1; and Figs. 7 and 8 are views in typical sectional elevation illustrating embodiments of the invention in modified form.

With reference now to the drawings and first to Figs. 1 to 6 thereof, 1 represents the outer wall and 2 the inner wall of an annular enclosure unit containing liquid 3 to the level of a bead 1a on its outer wall. The inner wall 2 is provided with a tapered part as at 2a, about which a collar designated 5, is disposed. This collar has a tapered part 5a seating upon the part 2a of the wall, and outstanding flange means including a part 5b below the level of the liquid 3 and which may be perforate as indicated, thereabout a part 5c disposed substantially at the surface of the liquid, and a peripheral part 5d downwardly turned and spaced somewhat from the outer wall 1.

A second enclosure unit comprises a top 6, a cylindrical filter element 7 and spaced thereabout a cylindrical wall part 8. The filter element 7 bears at its lower end upon the perforate part 5b of the collar 5 and at its upper end seats in the indicated annular recess in the cover 6, to which it is secured by a peripherally pronged washer 9. The wall member 8 is permanently secured with the indicated shoulder part of the cover member 6 as by welding. Centrally of the parts is a spindle 10 having its stem part 10a extending downwardly through the cover from a head part 10b. A washer 11 may be provided between the head part 10b and the cover 6, and washers 12 and 13 within the cover 6, the washers 9, 11, 12 and 13 as well as the cover 6 having central openings to receive the stem part of the spindle and being permanently secured with the spindle as by pinching of the latter at 14; the relation between the parts being such, however, that the spindle may be rotated in the cover 6 and the washer 9, and preferably also in the washer 12.

A fitting 15 having a through opening 16 is provided, and may include a bracket part 17 by which it may be mounted. The lower enclosure unit, containing the liquid 3, is positioned and supported upon this fitting 15, which latter for the purpose has an annular raised part 18 and thereabout a flange part 19. A bridge 20 extends across the opening 16 of the fitting 15 and carries a fixed nut 21 into which the threaded end of the spindle 10 may be turned. 55

to removably secure the upper enclosure unit in its indicated relation with the lower enclosure unit.

It will be evident that the parts are so proportioned and arranged, generally concentrically, that air flow may be had through the apparatus in a path as indicated by the arrows, and including an annular stretch A between the wall parts 1 and 8, a pass B radially inwardly, between the liquid 3 and the wall 8, a stretch C between the wall 8 and the filter element 7, radially inwardly through the filter element, to a stretch D between the filter element and the inner wall 2, in a downward stretch E through the inner wall 2, and thence directly outwardly through the opening 16 in the fitting 15.

The wall 8 in the assembly terminates substantially short of the level of the liquid 3. That the air velocity through the paths B over the wet surface provided by the liquid, may be adjusted relative to its velocity in other parts of the apparatus, and thereby be established as desired for a given demand condition upon said apparatus, a sleeve 8a is arranged in telescopic relation with the cylindrical wall 8, and means are provided for its securement in adjusted positions toward and from the liquid. Such means are here shown as slots 22 in one of the members, as the sleeve 8a, and cooperative bolts 23 extending through the other member, the wall 8.

By the arrangement just described, a single size of the apparatus may be adjusted to function properly through a wide range of conditions of demand on the apparatus, the conditions varying as to general velocity in the apparatus but the adjustment permitting the desired velocity at the pass E.

That the air stream in the stretch A may have a helical motion, a number of vane means 24 are provided in spaced relation about the center of the parts, to extend across the passage between the wall members 1 and 8. As is here indicated, each vane 24 is secured to the wall 8 as by rivets 24a. These vanes are of sheet metal and so proportioned and arranged as to provide yieldable bearing against the two wall members between which they extend so that concentricity of the wall members is yieldably maintained and rattling prevented in the assembly. The vane members 24 are also so proportioned, as indicated in Figs. 5 and 6, that they define a taper whereby the assembly between the two units will be facilitated. Also, the vane members are curved as indicated in Fig. 5, so that they bear with faces rather than edges, and consequently will not squeak when the apparatus is under vibration.

The part 5d of the collar 5 is sufficiently clear of the wall 1 so that the stretch A in the air passage is directed to the surface of the liquid 3 yet the part 5c lying substantially in the plane of the surface, is always maintained wet by liquid carried thereover by the air stream, if not by motion of the apparatus which, it will be appreciated, is usually employed upon an engine, often furnishing the propelling power for a vehicle. Yet the splash is limited by the parts 5c and 5d, against being sufficient to permit entrainment of liquid in the stream. The filter element 7 is, however, maintained wet, there being sufficient liquid agitation for the purpose, particularly in the trough formed by the part 5b. If the part 5b be perforate, uniform liquid level on each side of the part 5c will be substantially maintained. At any rate liquid level within the trough at the part 5b

will obviously be limited by the height of the part 5c.

The washer 12 is dished downwardly at its periphery as indicated, to trap liquid travelling from the filter element, on the under side of the cover 6, draining such liquid back into its container compartment and thereby preventing such liquid from finding its way to the outlet passages of the apparatus.

It will be apparent that the parts of the apparatus comprise three principal units as follows. The fitting 15 serves as a base part by which the apparatus has outlet connection to the carburetion device or whatever else the apparatus is to serve, and may serve also as a bracket to support the other parts of the apparatus;

The second unit of the assembly comprises the described enclosure unit for the liquid 3, and also includes the removable collar 5.

The third unit comprises those parts mounted upon the cover 6.

Units are releasably assembled by manipulation of the head 10b of the spindle 10, to control its threaded relation with the nut 21. In disassembly as for cleaning, the spindle being unscrewed, the upper unit of which the spindle forms a part is simply withdrawn upwardly and removed. The lower enclosure unit is then removed from the fitting 15 simply by lifting therefrom. The liquid 3 may be replaced and accumulated sludge easily removed by removal of the collar 5 from its seat.

Reassembly may obviously be conveniently had by reversing the order of the operations.

With reference now to the modification of Fig. 7, 31 is an annular enclosure unit having an inner wall 32 and containing a liquid 33. The unit is disposed about a tubular fitting 45 terminating at its upper end in a spider part 50. Removably mounted on this spider part by a thumb screw 40 is a cover 36 dependent from which is a cylindrical wall 38. Longitudinally adjustable on the wall 38, as by means of bolts 53, is a wall part 38a in the form of a sleeve as indicated. A filter element 37 is arranged to close the annular space between the sleeve 38a and the inner wall 32 of the container unit 31, and to be adjustable longitudinally of the inner wall 32 as by a beading 35. It will be apparent that the structure described provides a path for air flow through the apparatus including a downward stretch a, a pass b radially inwardly between the surface of the liquid 33 and the lower extremity of the sleeve 38a, upwardly through the filter element 37, along a stretch c inwardly between the arms of the spider 50, downwardly through the fitting 45, and from the apparatus. It will also be apparent that the filter element 37 will be maintained wet and clean by splash of the liquid 33 when the apparatus is subjected to vibration as in service. Adjustment of the sleeve 38a will control the relative velocity at the pass b generally as before, but in this case will effect adjustment of the filter element itself as well.

The modification of Fig. 8 shows apparatus designed for outlet of the filtered air in the upward direction by way of a fitting 75. To this fitting is clamped by means of an annulus 75a, a cover 66 having a cylindrical downwardly extending wall 68, the cover 66 being perforate to provide outlet from the cavity c' within the wall 68 by way of the passage e' in the fitting 75. An enclosure unit 61 is disposed about the wall 68 and removably mounted upon the latter in any con-

venient manner as by two or more spring bail members 70, secured in circumferentially spaced relation about the cylindrical wall part 61 of the outer unit, with end parts 70a extending over the edge of the cover 66. Guide vanes 84 are provided by deforming the wall part 68 outwardly at peripherally spaced locations, three being indicated. These vanes are themselves relatively rigid, but they bear upon the outer wall 61 with yieldable characteristic owing to the resilience of the wall 61 which may be slightly deformed by the bearing, and the wall 68 may be bowed slightly outwardly between the vanes 84 by the said bearing. A wall member or sleeve 68a is mounted upon the wall part at the lower extremity of the latter and for adjustment longitudinal of the same as by bolts 83. A discuate filter element 67 is mounted upon this sleeve member 68a to be effective at the mouth of the latter. A liquid 63 is provided in the bottom part of the container 61 so that a horizontal pass b' is provided in the air path through the apparatus between the surface of this liquid and the filter element 67.

Obviously, functioning of the apparatus will be generally as before, the path for air flow being downwardly through the annular stretch a', horizontally through the pass b', upwardly by way of the filter element 67, chamber c' and outlet passage e'. The filter element 67 is maintained wet and clean by splash of the liquid 63 and the velocity through the pass b' is adjustable substantially as in the preceding embodiment.

What we claim is:

1. In air filter apparatus characterized by an air path including a pass between a wet surface and a wall part extremity spaced therefrom, means for varying the operating characteristics of said apparatus by adjusting the velocity of flow through said pass relative to the velocity elsewhere in said path, and comprising means for adjusting the spacing of said wall part extremity from said wet surface.

2. In air filter apparatus characterized by an air path including a pass between a wet surface of substantial area and a wall part extremity spaced therefrom, said pass being immediately preceded by a stretch lengthwise of said wall and toward said extremity adjusting means for said extremity providing for a desired velocity of flow through said pass independent of a demand condition upon said apparatus.

3. In air filter apparatus characterized by an air path including a pass between a wet surface of substantial area and a wall part having an endless edge spaced therefrom, means for varying the velocity of flow through said pass relative to the velocity elsewhere in said path, and comprising sleeve means mounted for sliding adjustment upon said wall part relative to said surface.

4. Air filter apparatus containing a liquid providing a wet surface of substantial area, and having wall means providing an air path including a stretch directed toward said surface and thence a pass of which said surface is a boundary, said wall means including a stationary part spaced from said surface, and a part adjustable on said stationary part relative to said surface.

5. Air filter apparatus containing a liquid providing a wet surface, and having cylindrical wall means providing an air path including an annular stretch directed toward said surface and a radial pass thereover, said wall means including a stationary cylindrical part having a circular edge spaced from said surface, and a sleeve part tele-

scopically adjustable on said stationary part relative to said surface.

6. In air filter apparatus containing a body of liquid and having wall means providing an air path bounded in part by the surface of said liquid, stationary baffle means disposed substantially at said surface and having substantial extent therealong, to reduce splashing effect of said liquid during motion of said apparatus.

7. In air filter apparatus containing a body of liquid, having a filter element arranged to be washed by splash from said liquid during motion of said apparatus, and having wall means providing an air path by way of said filter element and bounded in part by the surface of said liquid, a stationary support for an end of said element, and having a part extending beyond said element, substantially at said surface and with substantial extent along the latter, to reduce said splash.

8. In air filter apparatus including a pair of enclosure units, each having one of a pair of cylindrical wall members, cooperative to form an annular air passage therebetween in the apparatus, said units being separable endwise of said wall members to provide cleaning access to the interior of the apparatus, vane means upon one of said wall members proportioned and arranged to define a taper adapted to facilitate assembly together of said units, with extent across said air passage to direct flow therethrough.

9. In air filter apparatus including a pair of enclosure units, each having one of a pair of cylindrical wall members, cooperative to form an annular air passage therebetween in the apparatus, said units being separable endwise of said wall members to provide cleaning access to the interior of the apparatus, vane means upon one of said wall members proportioned and arranged to define a taper adapted to facilitate assembly together of said units, and extending across said air passage with yieldable bearing upon the other member to yieldably maintain concentricity between said units.

10. In air filter apparatus including a pair of enclosure units separable to provide cleaning access to the interior of the apparatus, said units including a pair of cylindrical wall members, one on each, cooperative to form an annular air passage therebetween in the assembled apparatus, sheet metal vane means upon one of said wall members, extending across said air passage and turned to yieldably present a face part for bearing upon the other wall member to maintain concentricity between said units.

11. In air filter apparatus having a cylindrical filter element disposed extending downwardly from an end wall, means for maintaining said element wet, annular flange means extending from said end wall adjacent said element on the air outlet side of the latter, to limit liquid travel upon said wall from said element.

12. Air filter apparatus having an annular enclosure unit containing a liquid, the inner wall of said unit having a taper, a collar seating upon said taper and having flange means extending into said liquid, a cylindrical air filter element bearing endwise upon said flange means, and means providing releasable connection between the opposite end of said filter element and said enclosure unit.

13. In air filter apparatus containing a liquid and a filter element spaced from a surface part thereof to be wet by splash of said liquid in the operation of the apparatus, the air path through said apparatus including a pass between said

liquid and said filter element and leading to the latter, means for adjusting said element relative to said surface to vary the relative velocity of flow through said pass.

5 14. Air filter apparatus containing a liquid providing a wet surface, and having wall means providing an air path including a stretch directed toward said surface and thence a pass thereover, said wall means including a stationary part 10 spaced from said surface and a part adjustable on said stationary part relative to said surface, and a filter element mounted on said adjustable part and arranged to lie in said air path.

15 15. Air filter apparatus containing a liquid providing a wet surface, and having wall means providing an air path including a stretch directed toward said surface and thence a pass thereover, said wall means including a stationary part spaced 20 from said surface and a part adjustable on said stationary part relative to said surface, and a filter element mounted on said adjustable part and arranged to lie in said air path following said pass.

16. In air filter apparatus including a pair of enclosure units separable to provide cleaning 25 access to the interior of the apparatus, said units including a pair of cylindrical wall members, one on each, cooperative to form an annular air passage therebetween in the assembled apparatus, one of said wall members being deformed without 30 interruption to provide vane means extending into said air passage to direct flow in the latter along helical lines.

17. In air filter apparatus including a pair of enclosure units separable to provide cleaning 35 access to the interior of the apparatus, said units including a pair of cylindrical wall members, one on each, cooperative to form an annular air passage therebetween in the assembled apparatus, one of said wall members being deformed to pro-

vide vane means extending across said air passage to bear upon the other wall member.

18. In air filter apparatus including a pair of enclosure units separable to provide cleaning access to the interior of the apparatus, said units including a pair of cylindrical wall members, one on each, cooperative to form an annular air passage therebetween in the assembled apparatus, the inner of said wall members being outwardly deformed to provide vane means extending across 10 said air passage to bear upon the outer wall member.

19. In air filter apparatus including a pair of enclosure units separable to provide cleaning access to the interior of the apparatus, said units including a pair of cylindrical wall members, one on each, cooperative to form an annular air passage therebetween in the assembled apparatus, the inner of said wall members being outwardly deformed to provide vane means extending across 20 said air passage to bear upon the outer wall member, said wall members being so proportioned and arranged that said bearing will have resilient characteristics.

20. In air filter apparatus including a pair of enclosure units separable to provide cleaning access to the interior of the apparatus, said units including a pair of cylindrical wall members, one on each, cooperative to form an annular air passage therebetween in the assembled apparatus, 30 vane means upon one of said wall members, extending across said air passage with yieldable bearing upon the other wall member, to yieldably maintain concentricity between said units, and 35 adapted and disposed to impart helical components to flow through said passage.

ALBERT E. SCHAAF.
GEORGE M. WALTON.
